UNITED STATES PATENT OFFICE.

ALEXANDER WINTON AND HAROLD B. ANDERSON, OF CLEVELAND, OHIO, ASSIGNEES TO THE
WINTON MOTOR CARRIAGE COMPANY, OF CLEVELAND, OHIO.

MULTIPLE-CYLINDER TWO-CYCLE EXPLOSION-ENGINE.

No. 895,222.

Specification of Letters Patent.

Patented Aug. 4, 1908.

Application filed April 13, 1908. Serial No. 426,875.

To all whom it may concern:

Be it known that we, ALEXANDER WINTON and HAROLD B. ANDERSON, citizens of the United States, residing at Cleveland, in the county of Cuyahoga and State of Ohio, have invented certain new and useful Improvements in Multiple-Cylinder Two-Cycle Explosion-Engines, of which the following is a specification, reference being had therein to the accompanying drawing.

This invention relates to improvements in multiple cylinder two-cycle explosion engines, which utilize one carbureter for more than one cylinder, and the object of the present invention is to provide a means for controlling the richness of the explosive mixture to each individual cylinder independent of the carbureter.

As is well known to those skilled in this art, two-cycle engines draw the explosive mixture into the crank-case, compress it there, and transfer the compressed charge from the crank-case to the explosion cylinder. In multiple cylinder two-cycle engines there is a variation of compression in the individual crank-cases of the cylinders, on account of the variation in volume, and because of leakages which might be greater in one crank-case than in another. The leakage of the crank-cases will also vary from use, on account of the uneven wear in the crank-case bearings, and as a consequence uneven volumes are drawn to the individual crank-cases, which results in ununiform explosive mixtures for the individual cylinders. One or more cylinders will be found to get too rich a mixture, while the others are getting a proper mixture, or vice versa, and this cannot be cured by carbureter adjustment, because if the fluid supply is cut down to suit the overrich mixture, the mixture to the other cylinders will be too lean; or if the mixture to one or more cylinders is too lean, it cannot be cured by the carbureter adjustment without making the mixture to the other cylinder or cylinders too rich.

This improvement enables the explosive mixtures for the cylinders to be individually adjusted independently of the carbureter, and in that way the explosive mixture to the several cylinders is kept uniform, and of the proper richness to obtain the best results.

The invention is illustrated in the accompanying drawings, in which

Figure 1, is a top plan view of a multiple

cylinder two-cycle engine embodying the invention. Fig. 2, is a vertical, sectional view through one of the cylinders, showing the improvement applied thereto.

For the purpose of illustrating the present improvement, a three-cylinder two-cycle engine is herein shown, though it is to be understood that the invention is applicable to any number of cylinders more than one, and to any form of two-port or three-port two-cycle engine.

Referring now to the drawings, 1 are the cylinders, 2 the carbureter, and 3 the manifold piping connecting the carbureter with the crank-cases of the several cylinders. This manifold piping is so divided that there is the same length of travel for the gas between the carbureter and each crank-case. A throttle 4 is located between the carbureter and the manifold piping as is usual in such constructions.

The present improvement consists in providing each cylinder of the branches of the manifold piping with an atmospheric communication, here shown in the form of an L-shaped passage a, which is preferably placed close to the cylinder. This passage is controlled by an adjustable valve b, for regulating the amount of air that is admitted through the orifice a to the pipe.

The operation is, that when one or more of the cylinders are receiving a richer mixture than the others, because of wear of the crank-case bearings, or for any other cause, it is possible to bring the mixtures of the several cylinders uniform by admitting the proper amount of air through the orifice a to reduce the proportion of the richer mixture.

Suppose one cylinder is getting too rich a charge, which invariably happens for the reasons herein stated. If in this instance the carbureter is regulated to reduce the gasoline feed to feed the proper mixture to this cylinder, the mixture to the other cylinders will be correspondingly cut down, and the mixture for them will be too lean, and, of course, a decided loss of power: and furthermore, the lean charge is difficult to control at low speeds, as back-firing is likely to take place through the carbureter because the weak charge burns very slowly, setting fire to the gas in the crank-case, instead of being wholly burned by the time the exhaust port is opened, and before the gas inlet port is opened, as it should be.

By providing the adjustment in the gas supply pipe for each individual cylinder, we are enabled to make allowance for any variation in the mixture fed to the individual cylinders independently of the carbureter, and in this way cause the proper mixture to be fed to each cylinder, and thereby obtain the most efficient result.

Having thus described this invention, what is claimed, and desired to be secured by Letters Patent, is:—

1. The combination with a multiple cylinder two-cycle explosion engine, of a single carbureter having a supply communication for each cylinder, and means for admitting air to said communications independent of the carbureter.

2. The combination with a multiple cylinder two-cycle explosion engine, of a single

carbureter, a carbureter supply pipe for each cylinder, each of said pipes having an air inlet orifice independent of the carbureter, and means for controlling said orifices.

3. The combination with a multiple cylinder two-cycle explosion engine, of a single carbureter having a supply communication for each cylinder, and means for admitting regulated volumes of air to one of said communications independently of both the carbureter and the other communication. 30

In testimony whereof we affix our signatures in presence of two witnesses.

ALEXANDER WINTON.
HAROLD B. ANDERSON.
